UNITED STATES PATENT OFFICE.

STEWART J. CORT, OF BETHLEHEM, PENNSYLVANIA; TIMOTHY BURNS, OF BUFFALO, NEW YORK; AND ROBERT S. A. DOUGHERTY AND CHARLES E. LEHR, OF BETHLEHEM, PENNSYLVANIA.

REGENERATIVE OPEN-HEARTH FURNACE.

Application filed September 24, 1925. Serial No. 58,268.

Our invention relates to furnaces, and more particularly to furnaces of the regenerative open hearth type, and it has for an object to provide an improved water cooled liner and damper structure for the purpose of prolonging the life thereof.

In the construction of open hearth furnaces, it has been proposed to provide the ends thereof with resilient or monkey walls defining converging diverging passages affording communication between the furnace chamber and the gas and air ports. In order to better control a furnace of this type, it has been proposed to provide dampers at each end thereof, a damper being disposed at the throat of each of the converging diverging passages. Owing to the high temperatures of products of combustion passing through a converging diverging passage, both the walls thereof, as well as its damper, are likely to be burned out. Accordingly, therefore, it is an object of our invention to provide a furnace of this type which shall have a water cooled beam structure extending horizontally across the top of the furnace and in the region of the throat, this structure being provided with a damper slot, through which is movable a damper having a water-cooled rim, and the beam structure having secured thereto liners which are adapted to extend downwardly in opposed relation to edges of the damper and to define water-cooled sides for the passage. These and other objects are accomplished by our invention as will be apparent from the following description and the accompanying drawings, forming a part of this application, in which:

Fig. 1 is a fragmentary and longitudinal sectional view of a furnace embodying features of our invention;

Fig. 2 is a transverse sectional view taken along the line II—II of Fig. 1;

Fig. 3 is a fragmentary plan view of the apparatus illustrated in Fig. 1;

Fig. 4 is a sectional view of a damper;

Fig. 5 is a transverse sectional view of the damper rim;

Fig. 6 is a detail view of fastening means for securing the damper hood in place;

Figs. 7 and 8 are detail views of fastening means for the damper hood cover;

Fig. 9 is a horizontal sectional view taken along the line IX—IX of Fig. 1;

Figs. 10, 11 and 12 are detail views showing features of our improved water-cooled throat liner; and,

Figs. 13 and 14 are detail and fragmentary views of our improved roof beam structure.

Referring now to the accompanying drawings for a better understanding of our invention, we show a furnace or melting chamber, at 10, which is comprised by the hearth 11, parallel side walls 12, converging end walls 13, and an intermediate roof section 14, and end chambers, at 15, comprised by bottoms 16, converging side walls 17 and roof sections 18. The side walls 13 and 17 at each end of the furnace converge in opposite directions and are connected by the throats 19.

The end chambers 15 serve in a well-known manner as mixing or combustion chambers, gas being supplied thereto by the gas uptake 20 and air being supplied thereto by the air uptake 21.

The effective area of a throat 19 affording communication between the end chambers 15 and the furnace chamber 10 is varied or controlled by means of a transversely movable damper 23, which is movable through an opening in the roof of the furnace by a cable 24 passing over a sheave 25, the cable being connected to any suitable operating mechanism well-known to those skilled in the art and constituting no part of our present invention.

The damper illustrated is of a type old in the art and it preferably comprises a central body or core of refractory material consisting of brickwork 26 surrounded by a water-cooled frame 27, the latter being supplied with a perforated tube 28 connected to a source of compressed air and serving to stir up sediment in the frame 27. The frame is connected by tubes 29 and 30 to a cross bar 31, the latter being attached to the cable 24 already referred to. The tubes 29 and 30 also serve as outlet conduits for the rims, such tubes being connected to a common conduit 32 and the latter communicating by a hose connection 33 with a conduit 34 leading to the exhaust collector 35. The tube 29 has arranged therein a smaller tube

36 which communicates with a flexible hose section 37, the latter being coupled to a conduit 38 leading to a water supply manifold 39. The other conduit 30 encloses a 5 smaller conduit 40 connected by a hose 41 to a conduit 42 leading to a suitable supply of compressed air.

The throat portions 19 at the ends of the furnace are provided with vertical liners 10 44 which are oblong box-like metallic receptacles provided with water inlets 45 connected to tubes 46 terminating near the bottoms of the box-like receptacles. The inlets 45 are connected to conduits 47 leading 15 to the supply manifold 39. Each liner is provided with an outlet 48 at its upper end and the outlets are connected to discharge conduits 49, which lead to the exhaust receiver 35.

20 The lower ends of the liners 44 are held in place in suitable recesses 50 in the floor or bottom 16 and preferably fit against shoulders 51 provided at the side walls between transverse roof beams 53, to be more 25 particularly hereinafter described. The liners are preferably provided with laterally extending vertical ribs 54 which fit corresponding vertical grooves 55 in the beams 53. From the structure described, it will 30 be apparent that our improved liners 44 are readily removable from the furnace, it being only necessary to detach the conduit connections 47 and 49 and lift the liners upwardly. The pairs of cooperating beams 35 53 define damper entrance spaces 56 for the dampers 23 and serve to support the roof sections 14 and 18 in a manner to be referred to.

40 Each of the beam sections 53 is preferably L-shaped for the major portion of the length thereof and each section is provided with water cooling conduit openings 57 communicating with the manifold 39 and discharging to the exhaust receiver 35, the conduits being arranged near the surfaces of 45 the beams which define the damper entrance opening and near the bottom sides of the beams which are exposed to the heat of the furnace so as to effectively cool the beams 50 and to oppose burning out thereof due to the heat of the furnace.

The beams 53 are opposite and complementary in design so as to provide the damper entrance openings 56 and opposed 55 vertical slots 55 to receive the tongues 54 of the liners. Outside of the liners, the beams are provided with attaching portions 58 which are adapted to be attached by bolts or rivets 59 to opposed buckstays 60. The 60 beams 53 of a pair may furthermore be secured together by suitable bolts or keys 61.

As illustrated, the pairs of beam members 53 are arranged to extend transversely of the furnace above the throat portions 19 thereof, such throat portions being provided

by opposed reentrant or monkey walls comprised by the converging wall portions 13 and 17. The buckstays 60 are arranged exteriorly of the furnace and fit against the outside of the reentrant walls and serve to 70 reinforce the latter. In addition to the buckstays 60, the furnace is also equipped with other buckstays 63 spaced wider apart for reinforcing the walls of the furnace.

The beam structures, comprised by the 75 pairs of complementary beam members 53 serve to divide the furnace roof into a plurality of sections, whereby a section may be removed or repaired without disturbing other sections. Where the roof of the furnace is a unitary piece of masonry construction, it will be apparent that repairs and replacements cannot be localized to isolated sections but that the entire roof must generally be replaced. Our transverse beam 80 structure, therefore, affords a roof construction such that the end sections 18 may be replaced or repaired without affecting the central section 14, and the latter section may be removed or repaired without affecting 85 the end sections. As illustrated, the roof section 18 is inclined slightly downwardly toward the furnace chamber 10, whereby lateral thrust is imposed upon the transverse beam structure. The transverse beam structures, therefore, not only serve to isolate the 90 roof into a plurality of sections but also serve to support or resist any lateral thrusts incident to the design of the roof sections.

95 In order to minimize the leakage of gases 100 through the space 56 and around the damper 23, we provide a hood at 65, which extends above the roof of the furnace and constitutes a pocket or receptacle for enclosing the damper when the latter is elevated. The 105 hood is preferably comprised by a metallic shell 66 which embraces refractory material 67, the latter defining a damper pocket or receptacle 68. The shell 66 is provided with flange means 69 at the bottom, the flange means 69 resting on the beams 53 and being 110 preferably secured to the latter by detachable key means 70, such as illustrated in Fig. 6. The key means referred to may be comprised by bolts 71 which pass through 115 openings 72 in the beam members 53 and registering openings 73 in the flange means 69, the bolts being provided with transverse slots to receive wedge keys 78. From the structure described, it will, therefore, be 120 apparent that the hoods 65 may be readily attached and detached from the beam structures.

125 The shells 66 are preferably provided with flanges 75 near the tops upon which fit the top sections 76, the latter being notched at 77 to receive L-shaped keys 78 fitting in openings 79 in the flanges 75 and held in place by transversely extending wedges 80 as shown in Fig. 8. The cover for the hood 130

is preferably made in complementary sections in order to provide for its ready attachment and removal. In removing the hood construction, the complementary parts 76 of a

5 cover are first removed, then the damper is elevated up through the opening or pocket 68 and above the hood structure 65, whereupon the keys 70 may be removed and the hood structure taken off.

10 From the foregoing description, it will be apparent that we have provided a furnace having reentrant monkey walls with water-cooled or heat resisting liners in order to protect such walls at points most likely to 15 burn out. It will also be apparent that we have provided transverse beam structures which are water-cooled, such beam structures serving to define damper entrance openings, to divide the furnace roof into 20 a plurality of sections and to serve as tying means for opposed buckstays 60, the latter cooperating to afford lateral support for the reentrant monkey walls. In addition, it will also be seen that we provide a hood 25 construction for the damper, whereby only openings for the conduits 29 and 30 must be provided and the leakage of gas around the damper to the outside is effectively limited.

30 While we have shown our invention in but one form, it will be obvious to those skilled in the art that it is not so limited, but is susceptible of various other changes and modifications without departing from 35 the spirit thereof, and we desire, therefore, that only such limitations shall be placed thereupon as are imposed by the prior art or as are specifically set forth in the appended claims.

40 Having thus described our invention, what we claim as new and desire to secure by Letters Patent is:

1. In a regenerative furnace, in combination, a pair of opposed buckstays, water-cooled beams secured to opposite sides of

the buckstays, and water-cooled members having key and slot connections with the beams.

2. In a regenerative furnace, in combination, a pair of opposed buckstays, spaced 50 water-cooled beams secured to the buckstays and having opposed vertical slots near each end, and water-cooled members having tongues at their upper ends fitting in the slots.

3. In a regenerative furnace, an arched 55 roof structure comprising two masonry sections and an intermediate section, said intermediate section including a water-cooled horizontal and transverse beam structure, 60 and means maintaining said beam structure in engagement with one of said masonry sections in a manner to resist end movement of one masonry section toward the intermediate section.

4. In a regenerative furnace, an arched 65 roof structure comprising two masonry sections and an intermediate section, said intermediate section including a water-cooled horizontal and transverse beam structure, 70 and means maintaining said beam structure in engagement with one of said masonry sections in a manner to resist end movement of one masonry section toward the intermediate section, said means including opposed buckstays at opposite sides of the furnace attached to said transverse beam structure.
